UNITED STATES PATENT OFFICE.

WALTER L. BETTS, OF BROOKLYN, NEW YORK, ASSIGNOR TO WESTERN ELECTRIC COMPANY, INCORPORATED, OF NEW YORK, N. Y., A CORPORATION OF NEW YORK.

VIBRATION-PROOF VACUUM-TUBE MOUNTING.

1,364,860.

Specification of Letters Patent. Patented Jan. 11, 1921.

Application filed August 12, 1919. Serial No. 317,092.

To all whom it may concern:

Be it known that I, WALTER L. BETTS, a citizen of the United States, residing at Brooklyn, in the county of Kings, State of New York, have invented certain new and useful Improvements in Vibration-Proof Vacuum-Tube Mountings, of which the following is a full, clear, concise, and exact description.

10 This invention relates to supports for vacuum tubes, and more particularly to a support which will absorb substantially all vibrations which would otherwise be imparted to the vacuum tube from the structure on which it is mounted.

In amplifier circuits particularly of the multi-stage type employing a number of vacuum tubes such as six or seven or more in cascade, it has been found that very minute vibrations of the electrodes of the first tubes produce variations in their output currents which when reamplified by the succeeding tubes are of such magnitude as to seriously interfere with, if not render impossible, the 25 detection of the signals which are to be amplified.

It is the object of this invention to provide a mounting for one or more of the vacuum tubes in an arrangement of this kind which will absorb substantially all the vibrations which may occur in the main supporting structure.

In the form of the invention shown herein, the tube is mounted on a yielding member comprising two sheets of sponge rubber connected by a metallic plate and this yielding member is in turn mounted on a second yielding member comprising a sheet of sponge rubber at right angles to the first member and suitably attached at its ends to the main supporting structure.

This invention is an improvement on the vacuum tube supporting structure disclosed and broadly claimed in the application of Roy M. Allen, Serial No. 236,398, filed May 24, 1918.

The above and other objects of the invention will be more clearly understood from the following detailed description and claims taken in connection with the accompanying drawing, in which the figure is a perspective view, partly broken away, showing one embodiment of the invention.

Referring to the drawing by reference

numerals the base members 1 may rest upon or be secured to a casing or other structure in connection with which the vacuum tube is to be used. While the base members are shown in a horizontal position, it is, of course, obvious that they might be attached in any desired position. To the upper edges of these members 1 is attached a sheet of sponge rubber 2 by suitable securing means 3. Secured to the member 2 at a spaced interval from the base members are two yoke-shaped members 4 and secured to each of the yoke members 4 in a plane at right angles to member 2 is a sheet of sponge rubber 5, the sheets 5 lying in the same plane and being attached together by the metallic plate 6 having an opening 7 therethrough.

Mounted adjacent the opening 7 is a clamping member 8 adapted to clamp the base of a vacuum tube 9. While the invention is of course not limited to use with any particular form of vacuum tube, the tube may, for example, be of this type shown in United States patent to Harold DeForest Arnold, No. 1,129,942, dated March 2, 1915. It is, of course, obvious that any suitable or usual vacuum tube socket may be used in place of the clamping member 8. In the form shown, the leads 10 may be attached to the external electrodes of the tube in any suitable manner as by soldering and the leads 10 are secured to the sheet of sponge rubber 2 by plates of insulating material 11. Leads should be used which are flexible and so looped that a minimum of vibration is brought in over them.

While one embodiment of the invention has been illustrated and described it is to be understood that the invention is not limited to the specific form shown but is entitled to the equivalents thereof within the scope of the appended claims.

What is claimed is:

1. A vibration-proof vacuum tube mounting comprising a plurality of yielding members serially interposed between the tube and the supporting structure, one of said yielding members having its plane of most free movement at right angles to the plane of the most free movement of another of said members.

2. A vibration-proof mounting for vacuum tubes comprising a sheet of yielding material, a second sheet of yielding material

secured to said first sheet at a substantial angle thereto, and means for securing the vacuum tube to said second-mentioned sheet.

3. A vibration-proof mounting for vacuum tubes comprising a sheet of sponge rubber, a second sheet of sponge rubber at a substantial angle to said first sheet, and means for securing said vacuum tube to said second sheet.

10 4. A vibration-proof mounting for vacuum tubes comprising a sheet of yielding material attached at its ends to supporting means, a second sheet of yielding material secured to said first sheet at a substantial angle thereto, and means for securing said vacuum tube to said second sheet.

5. A vibration-proof vacuum tube support comprising a sheet of yielding material attached at its ends to supporting means, a 20 second sheet of yielding material secured to said first sheet at an angle thereto and intermediate the ends of said first sheet, and means for securing a vacuum tube to said second sheet.

25 6. A vibration-proof mounting for vacuum tubes comprising a sheet of sponge rubber supported at its ends, a member secured to said sheet at an angle thereto and comprising two sheets of sponge rubber con-

nected by a rigid plate, and means for securing a vacuum tube to said plate.

7. A vibration-proof mounting for vacuum tubes comprising a sheet of sponge rubber supported at its ends, a pair of yoke-shaped supporting members secured to said sheet, a yielding member secured to said yoke-shaped member, and means for securing a vacuum tube to said yielding member.

8. A vibration-proof mounting for vacuum tubes, comprising a supporting structure 40 and a plurality of yielding members serially interposed between the tube and said supporting structure, one of said members being adapted to absorb most efficiently vibrations in one plane, and another of said members 45 being adapted to absorb most efficiently vibrations in another plane.

9. A vibration-proof mounting for vacuum tubes, comprising base members, a yielding member mounted on said base members, 50 a support on said yielding member, a second yielding member connected to said support, and means for connecting a vacuum tube to said second yielding member.

In witness whereof, I hereunto subscribe 55 my name this 8th day of August, A. D. 1919.

WALTER L. BETTS.
